UNITED STATES PATENT OFFICE.

JAMES E. GROSJEAN, OF LIMA, OHIO.

SOLE FOR BOOTS AND SHOES AND METHOD OF MAKING THE SAME.

Application filed September 4, 1923. Serial No. 660,878.

To all whom it may concern:

Be it known that I, JAMES E. GROSJEAN, a citizen of the United States, residing at Lima, in the county of Allen and State of Ohio, have invented new and useful Improvements in Soles for Boots and Shoes and Methods of Making the Same, of which the following is a specification.

The present invention relates to improvements in soles or half-soles for boots and shoes, and more particularly to composite soles of the kind comprising strips or plies of rubber and textile material set edgewise, or substantially so, to the tread or wear surface of the sole and extending to its peripheral edge, soles of this type being especially suitable for workingmen's shoes and for similar uses where the edge of the sole must possess great strength and wear-resisting qualities, it having been found that when soles having a surrounding edge or margin of rubber are subjected to hard usage, the rubber edge prematurely wears and thus impairs or destroys the shoe.

I have found that if it is attempted to construct a sole of this type by extending the alternate strips of rubber and textile or fabric directly from edge to edge of the sole, short length strips will result at certain points in the periphery of the sole, and also, the strips at certain points will unavoidably extend lengthwise with the adjacent edge of the sole, and these short length strips or those extending lengthwise with the edge of the sole, particularly those at the toe of the sole, would break off under the hard usage to which such shoes are usually subjected.

The primary object of the present invention is to provide a novel and improved sole or half-sole of the type above described but which avoids the foregoing and other objections, the sole, according to the present invention, having the alternate rubber and textile strips set on edge, or substantially so, and extending to the peripheral edge of the sole, but the strips are so arranged and assembled at the edge of the sole that they will not strip off or break off under the severe strains and wear to which shoes of this type are usually subjected, the strips, according to the present invention, being so arranged and assembled that there are no short length strips exposed at the edge of

the sole, and moreover, all of the strips extend endwise to the exposed edge of the sole. 55

Another object of the invention is to provide a reinforcement for securing the shank end of a half-sole of this or a similar type to the shank of the sole, whereby breakage of the sole at this point under severe strains 60 is effectually prevented.

To these and other ends the invention consists in certain improvements and combinations and arrangements of parts, all as will be hereinafter more fully described, the features of novelty being pointed out particularly in the claims at the end of the specification.

In the accompanying drawings:—

Figure 1 is a bottom plan view of a shoe 70 sole constructed in accordance with one embodiment of the invention.

Figure 2 is a bottom plan view of the sole during its course of manufacture and prior to its final assembly and curing. 75

Figure 3 is a view similar to Figure 2 but showing another mode of uniting the shank end of a half-sole to the shank of the sole.

Figure 4 represents on an enlarged scale 80 a longitudinal section taken through the shank portion of the sole prior to curing and illustrating the reinforcement for uniting the shank end of the half-sole to the shank portion of the sole.

Figure 5 is a view similar to Figure 4 but 85 showing the reinforcement and adjacent portions of the sole after curing.

Soles or half-soles constructed in accordance with the present invention are capable of use generally on boots and shoes, although 90 they are particularly suitable for use on boots and shoes intended to be worn by workmen where the soles, and particularly the edges thereof, are subjected to severe strains and wear. In order to afford the 95 requisite strength and wear-resisting qualities at the edge of the sole, as well as in the body of the sole, it is desirable to construct the sole of alternate strips of textile material, preferably woven fabric impregnated 100 with rubber, similar to the fabric used in automobile tire casings, or cord fabric impregnated with rubber, similar to the cord fabric used in the casings of cord automobile tires, the strips of fabric alternating with 105 strips or plies of uncured rubber, the strips

of fabric and rubber being extended across the sole from edge to edge. I have found, however, that if it is attempted to extend the fabric and rubber strips directly across the sole from edge to edge, the strips at certain points in the edge of the sole will be relatively short, and at other points in the edge of the sole the strips will extend lengthwise or substantially parallel with such edge, and these short length strips or the strips which extend lengthwise with the exposed edge of the sole will be easily broken or stripped off from the sole, under the stresses or wear to which the sole is subjected, thereby impairing the boot or shoe.

According to the present invention the forward portion of the sole is constructed of alternate strips or plies of rubber, designated 1, and textile material or fabric, designated 2. In using cord fabric, the strips are so prepared that the ends of the cords will be presented endwise to the tread or wear surface of the sole, this being also true when the textile strips are prepared from woven fabrics, such as canvas. The strips may be prepared in any suitable way, as, for example, by superposing plies of the textile material and rubber in sheet form, then cutting strips from the plied sheet, and then assembling the strips so that the plies stand edgewise or substantially so to the tread or wear surface of the sole, the ends of the threads or cords of the textile plies being presented endwise to the tread or wear surface. In making up a half-sole from the strips of rubber and textile material assembled in the manner above described, it is preferable to cut out by dies or otherwise, sections 3 and 4 which are adapted to be placed together and united along a longitudinal line 5 to form the half-sole, these sections being so cut that the rubber and textile strips of the sections will extend diagonally of the length of the sole, the strips of one section preferably extending at a diverging angle with respect to the strips of the other section, so that the strips of the two sections, when assembled, will form what may be termed a herringbone arrangement. The toe end of the section 3 is formed with a notch 6, this notch having a tongue-like portion 7 beyond it, the edge 8 of which diverges outwardly with respect to the longitudinal or medial line 5. Similarly, the section 4 is formed with a notch or cut-out portion 9 which leaves a tongue-like portion beyond it, and the edge 11 of this portion 10 diverges outwardly from the longitudinal or medial line 5 of the section 4. The edges 6 and 9 of the notches 6 and 9 form a continuous line when the sections 3 and 4 are assembled in proper registration, and this line is preferably approximately parallel with the edge of the toe end of the sole which is to be produced. The tongue-like portions 7

and 10 of the two sections are of such length that when these tongue-like portions are bent inwardly to close the notches 6 and 9 the edges 8 and 11 will meet, and preferably these edges 8 and 11 are arranged to meet on a line which will form a continuation or extension of the meeting line 5 of the two sections. The shank end of the half-sole may be provided with somewhat similar notches or cut-out portions 12 and 13 adjacent to the meeting line 5 of the two sections, these notches leaving portions 14 and 15 of the sections at their outer sides which may be bent edgewise inwardly to close the notches.

In making a sole embodying the present invention, the heel and shank portion thereof, designated 16, may be prepared from a sheet of uncured rubber composition cut to the proper form and the forward portion of the sole may be composed of the composite sections 3 and 4, the two parts of the sole being placed together in a curing mold having the form which the finished sole is to have, the tongue-like portions 7 and 8 toward the toe of the sole being bent inwardly to close the notches 6 and 9 and to cause the edges 8 and 11 to meet and the portions 14 and 15 being also bent inwardly until the notches 12 and 13 are closed, the form of the sole at this time being substantially as shown in Figure 1. The sheet or layer of rubber or rubber compound 17 may be applied to the upper side of the forward portion of the sole comprising the sections 3 and 4, this rubber ply holding this part of the sole in shape for curing and a longer sheet or ply of rubber-impregnated canvas 18 is preferably applied to the top of the sheet 17 and to the upper side of the rear portion 16 of the sole, this latter canvas strip holding the parts of the sole together preparatory to curing. Rubber may be applied to the edges of the notches and to the edges 8 and 11 before the sole in process of manufacture is placed in the mold, and the heat and pressure applied to the sole while undergoing curing within the mold permanently and firmly unites the constituent parts of the sole and vulcanizes the portions 7 and 10 and 14 and 15 in the position shown clearly in Figure 1.

It will be observed in Figure 1 that the strips of rubber and textile material extend in a lengthwise direction to the front or toe edge of the sole and that these strips are of substantial length. It will also be understood from Figure 1 that the portions 14 and 15 are drawn inwardly or toward the longitudinal center of the sole so that the strips which otherwise would be exposed at the outer edge of the sole are caused to occupy positions within the edges 19 of the shank portion of the sole and, hence, these short strips will be protected.

Figure 3 shows a half-sole made in a man-

ner somewhat similar to that illustrated in Figures 1 and 2, the front or toe end of the sole being notched and re-formed in the same manner as shown in Figures 1 and 2. The 5 rear or shank edge of the half-sole, however, instead of being notched, as shown in Figures 1 and 2, is provided with saw teeth or serrations 20 and 21 along the edges thereof adjacent to the short length rubber and 10 fabric strips. When a sole of this kind is placed in the mold and cured, the serrations 20 and 21 enable the rubber compound at the point where it joins the shank of the rear portion of the sole to become interlocked therewith and also to form a strong vulcanized joint which securely holds the rubber and fabric strips in proper place in the sole, 15 enabling these strips to effectually withstand stresses tending to dislodge them.

20 In order to reinforce the sole at the joint between its forward and rear portions, and thus avoid breakage at this point under severe stresses, a strip of strong, tough fabric, such as heavy canvas 22, bearing a 25 layer of uncured rubber 23, is preferably inserted so that its front end overlaps the rear edge of the forward portion of the sole formed by the sections 3 and 4 and its rear end underlies the rear portion 16 of the 30 sole. The mode of inserting this reinforcing strip is shown in Figure 4. When the sole is cured, the fabric or canvas strip 22 will become vulcanized within the sole, and it will extend across the joint formed between 35 the front and rear portions of the sole, substantially as shown in Figure 5, it thus acting as a tie to effectually prevent breakage or separation of the sole at the joint.

40 By notching the toe portion of the sole and then bending or drawing inwardly the portions of the sole at the outer sides of the notches or cut out portions until their edges meet, the short-length rubber and fabric strips which would otherwise exist at the 45 toe along the medial line of the divergently-related strips are eliminated, and they are replaced by relatively long-length strips which are securely held in place and are capable of resisting the stresses to which the toe of the 50 sole is subjected, especially in shoes worn by workmen. By notching the edge of the sole comprising the strips where it joins the shank of the sole and bending or drawing inwardly the portions of the sole at the 55 outer sides of these notches, the relatively short strips are drawn inwardly so that they lie within the outer edge of the shank portion of the sole and hence these short strips are protected and they therefore will not 60 be subjected to stresses which otherwise might strip or break them away from the sole. Also, by rounding the rear corners of that portion of the sole which comprises the strips and forming teeth or serrations 65 in or adjacent to the short strips, the latter

become securely vulcanized and keyed to the shank portion of the sole and hence breaking away of these strips is prevented.

The arrangement of the strips of rubber and textile material at relatively divergent angles extending (preferably at about 45°) from opposite sides of a medial line possesses substantial advantages over structures heretofore proposed, it facilitating manufacture and enabling relatively small pieces of material to be utilized and in use, it presents a surface which will possess substantially uniform wear-resisting properties throughout its area and it will effectively resist slipping in any direction. It provides a tough wear-resisting edge of the sole, and when formed at the toe and shank as heretofore described, the edge of the sole is not subject to breakage or similar damage.

45 The soles or half-soles are preferably made in accordance with the method herein described, such method enabling the plied material to be cut out readily by dies to form blanks or complemental sections of the proper form, and after the complemental sections are joined, and the material adjacent to the notches has been drawn or forced inwardly to close the notch and bring the portion of the sole in course of manufacture into substantially the form of the finished sole, the rubber ply 17 may be applied whereby the sections will be held in proper form, and after the rear portion 16 of the sole and the ply 18, as well as the reinforcement 22 have been assembled, the whole may be placed in a mold of suitable size and form and cured, whereby the sole will be given its permanent finished form and all parts composing the sole will be securely united by vulcanization.

55 I claim as my invention:—

1. A sole for boots and shoes comprising complemental sections joined on a line extending substantially longitudinally of the sole, said sections comprising strips of fabric set substantially edgewise to the tread surface of the sole, the strips extending divergently from said line toward the respective edges of the sole.

60 2. A sole for boots and shoes comprising strips of material extending at divergent angles toward opposite edges of the sole, the strips at a portion of the sole being notched and the edges of the notch brought together whereby the portions of the strips at one side of the joined edges of the notch extending in a different direction relatively to the portions of the strips at the other side of the joined edges of the notch.

65 3. A sole for boots and shoes comprising plies of material presented edgewise to the tread surface of the sole and extending divergently from a line extending longitudinally of the sole and toward the opposite edges of the sole, strips at opposite sides

- of the longitudinal line being notched and the edges of the notches brought together at points removed inwardly from the edge of the sole and the strips between the joined edges of each notch and the edge of the sole extending in a different direction relatively to those at the other side of the joined edges of the notch.
4. A sole for boots and shoes comprising 10 plies of material presented edgewise to the tread surface and extending divergently from a line extending substantially longitudinally of the sole toward the side edges thereof, the strips in the region of the toe 15 end of the sole being interrupted on a line which intersects said longitudinal line and is substantially parallel to but is removed inwardly from the toe edge of the sole, the strips extending from said line of interruption to the toe edge of the sole in a direction substantially longitudinal of the sole.
5. A sole for boots and shoes comprising 20 assembled strips of material presented edgewise to the tread surface and extending divergently toward the side edges of the sole, the strips adjacent to the shank of the sole being interrupted and extending in relatively different directions at the respective sides of the interruption.
6. A sole for boots and shoes comprising 25 strips of material extending divergently toward the respective side edges of the sole, a portion of the sole being notched and the edges of the notch brought together whereby 30 the direction of the strips between the joined edges of the notch and the adjacent edge of the sole is altered.
7. A sole for boots and shoes comprising 35 strips of material extending divergently toward the side edges of the sole, the toe portion of the sole being notched and the edges of the notch brought together whereby 40 the strips between said joined edges and the toe edge of the sole extend substantially longitudinally of the sole.
8. A sole for boots and shoes comprising 45 assembled strips of material extending divergently toward the side edges of the sole and having an edge adjacent to the shank portion which is notched, and the edges of 50 the notch drawn inwardly and united.
9. A sole for boots and shoes comprising 55 a forward portion composed of strips of material presented substantially edgewise to the tread surface, a rear portion, and a reinforcement composed of tough textile material which overlaps the adjacent edges of the forward and rear portions of the sole and is vulcanized thereto.
10. A sole for boots and shoes comprising 60 forward and rear portions joined adjacent to the shank, and a reinforcement composed of fabric which bridges the joined edges of 65 said portions of the sole and is vulcanized thereto.
11. The improvement in the manufacture of soles for boots and shoes which comprises forming a notch in a sheet made up of plies of material assembled to present their edges to the surfaces of the sheet, and drawing together and uniting the material at the edges of the notch to shape the sheet to conform substantially with the outline of the sole to be produced.
12. The improvement in the manufacture 75 of soles for boots and shoes which comprises cutting a blank from a sheet of material made up of plies of material assembled to present their edges to the surface of the sheet, the blank approximating the outline 80 of the sole and having a notch therein and toward one end thereof which intersects some of the strips, drawing together the edges of the material at opposite sides of the notch and to shape the sheet to conform 85 substantially with the outline of the sole to be produced to close the notch, and uniting said edges of the material.
13. The improvement in the manufacture 90 of soles for boots and shoes which comprises 95 assembling sections made up of strips of material extending divergently from a medial line, the assembled sections approximating the outline of the sole and having a notch formed in one end which intersects the adjacent strips, drawing together the material of the sections at opposite sides of the notch to close the latter and to shape such portions of the sections to conform 100 substantially with the shape of the sole to be produced, and then curing the sole.
14. The improvement in the manufacture 105 of soles for boots and shoes which comprises assembling a pair of sections made up of plies of material presented edgewise to the surface and extending divergently from the line of jointure of the sections, the assembled sections approximating the outline of 110 the sole to be made therefrom and having a notch formed in one end which extends across the line of jointure of the sections, forcing together the material of the sections to close said notch and to bring the adjacent portions of the sections into substantial 115 conformity with the shape to be given such portion of the finished sole, and then curing the sole and thus uniting the material at the edges of the notch.
15. The improvement in the manufacture 120 of soles for boots and shoes which comprises 125 assembling sections made up of strips of material extending divergently from a medial line, the assembled sections having a notch which intersects the adjacent strips, drawing together the material of the sections at opposite sides of the notch to close the latter and to shape such portions of the sections, applying a ply of vulcanizable material to the sections thus shaped, and curing the sole.

16. The improvement in the manufacture of soles for boots and shoes which comprises assembling complementary sections made up of strips of material extending divergently from a line of jointure of the sections, the assembled sections having a notch which intersects the adjacent strips and also said line of jointure, drawing together the material of the sections at opposite sides of the notch to close the same and shape such portions of the sections, applying a ply of vulcanizable material to a face of the assembled sections while so shaped, and curing the sole.

In testimony whereof I have hereunto set my hand.

JAMES E. GROSJEAN.
